UNITED STATES PATENT OFFICE.

FREDERICK J. HESS, OF CHICAGO, ILLINOIS.

HOLDBACK ATTACHMENT FOR VEHICLES.

SPECIFICATION forming part of Letters Patent No. 622,145, dated March 28, 1899.

Application filed March 26, 1898. Serial No. 675,234. (No model.)

To all whom it may concern:

Be it known that I, FREDERICK J. HESS, residing at Chicago, in the county of Cook and State of Illinois, have invented certain new and useful Improvements in Holdback Attachments, of which the following is a specification.

My invention relates to an improved holdback attachment for use principally in connection with single rigs, where a pair of shafts or thills are employed; and it consists of a simple and easily-adjusted connection between the holdback-straps and the thills, and it is designed to furnish such a connection that while it is extremely simple, and capable of easy adjustment, it shall be practically incapable of accidental displacement.

Referring to the annexed sheet of drawings, in which the same letters of reference are used to designate identical parts in all the views, Figure 1 is a side elevation of the attachment mounted in place upon a thill. Fig. 2 is a plan view of the same in section on the line 2 2 of Fig. 1, and Fig. 3 is a perspective view showing the relative position of the parts just prior to connection or subsequent to disconnection.

A is the thill, and mounted thereon is the thill-connecting member B, the essential part of which is the loop portion B', which may be connected to the thill by means of the screws B³ in the ends of the plate B², which I employ as a basis for this connecting member, although it will be understood that the portion 35 of the base B² between the ends of the loop portion B' is not essential and may be entirely omitted.

The holdback-strap member C is composed of the portion C', which is conveniently of a triangular shape and has therein the slot C², through which the holdback-strap D passes. The loop-engaging portion C³ of the member C may also be of a substantially triangular shape and is provided with the aperture C⁴ 45 therein, which is of sufficient size to readily accommodate the thickened end portion B⁵ of the loop B'. Leading from this aperture C⁴ to the outer edge of the part C³ is the slot C⁵, which is just of sufficient width to permit 50 the easy passage therethrough of the thin portion B⁴ of the front end of the loop portion B'. This slot C⁵ might lead from the aperture C⁴

in some other direction than the one shown, which is in line with the longest axis of the holdback-strap member C.

55

The operation of the device will be readily apparent. In hitching up the horse after the tugs are fastened the parts are brought into the position of Fig. 3, when the member C can be readily engaged with the member B by 60 passing the slot C⁵ over the thin portion B⁴ of the loop, and the parts then swing back to their normal position, as shown in Fig. 1. When the parts are connected, as shown in Fig. 1, it is practically impossible to disengage them accidentally, as has been possible with all previous holdback attachments with which I am familiar.

What I claim, and desire to secure by Letters Patent of the United States, is— 70

1. A holdback attachment for harness comprising the continuous loop member B' adapted to be fastened to the thill and having the reduced portion substantially oblong in cross-section, with the strap D, and the strap member C movably attached to the strap D and having an aperture therein corresponding in size to the cross-section of the largest portion of the co-operating loop and a slot leading thereto corresponding in width to the lesser diameter of the reduced portion and in the normal position of the parts arranged at right angles to the axis of the greater diameter of the reduced portion, substantially as described. 75

2. A holdback attachment for harness comprising the continuous loop member B' adapted to be fastened to the thill and having a reduced portion at its forward end substantially oblong in cross-section with its lesser diameter parallel to the line of the loop; with the strap D; and the strap member C movably attached to the strap D consisting of a rigid attachment having an aperture therein corresponding in size to the cross-section of the largest portion of the co-operating loop, and a slot leading thereto corresponding to the lesser diameter of the reduced portion of the loop member and arranged in the normal position of the parts parallel to said lesser diameter, substantially as described. 80 85 90 95
